UNITED STATES PATENT OFFICE

147,707

DESIGN FOR A DOLL

Elsie Gilbert Winterfeld, New York, N. Y., assignor to Three-In-One Doll Corporation, New York, N. Y., a corporation of New York

Application December 15, 1945, Serial No. 124,788

Term of patent 14 years

(Cl. D34—4)

To all whom it may concern:

Be it known that I, Elsie Gilbert Winterfeld, a citizen of the United States of America, and who am a resident of New York, in the county of the Bronx and State of New York, have invented a new, original, and ornamental Design for a Doll, of which the following is a specification, reference being had to the accompanying drawings, forming part thereof.

In the drawings:

I claim:

The ornamental design for a doll, substantially as shown.

ELsie GILBERT WINTERFELD.
